CLAIM

The ornamental design for a pod for use with a food or drink machine, substantially as shown and described.

DESCRIPTION

FIG. 1 is a top perspective view of a pod for use with a food or drink machine, showing our new design;

FIG. 2 is a bottom perspective view thereof;

FIG. 3 is a front elevation thereof, the rear, right and left side elevation views being identical thereto;

FIG. 4 is a top plan view thereof; and,

FIG. 5 is a bottom plan view thereof.
